UNITED STATES PATENT OFFICE.

ISAAC KARPEN, OF CHICAGO, ILLINOIS, ASSIGNOR TO S. KARPEN & BROS., OF CHICAGO, ILLINOIS, A CORPORATION OF WEST VIRGINIA.

SPRING STRUCTURE.

1,226,219.

Specification of Letters Patent. Patented May 15, 1917.

Application filed August 8, 1915. Serial No. 44,061.

To all whom it may concern:

Be it known that I, ISAAC KARPEN, a citizen of the United States, residing at Chicago, in the county of Cook and State of Illinois, have invented a new and useful Improvement in Spring Structures, of which the following is a specification.

My invention relates particularly to spring structures adapted for use in cushions, mattresses and the like; and my primary object is to provide an improved structure in which the individual coil springs, while thoroughly isolated from each other, are nevertheless so connected as to afford great durability and stanchness, coupled with most agreeable yielding resilience. A further object is to simplify and cheapen the method of construction.

The invention is illustrated in the preferred embodiment in the accompanying drawings, in which—

Figure 1 represents a broken plan view of a spring structure embodying my invention, associated with a casing for the spring structure (shown brokenly); Fig. 2 represents a broken elevational view of an elongated flexible envelop divided into spring-cells, such envelops extending in one direction in the spring structure; Fig. 3, a broken sectional view taken as indicated at the line 3 of Fig. 1, and illustrating the manner in which envelops of the kind shown in Fig. 2 are threaded through envelops of the kind shown in Fig. 4 (the springs being first inserted in the cells); Fig. 4, a broken elevational view of a flexible envelop which is divided into cells and provided with vertical slits, such envelops being disposed in the spring structure at right angles to the envelops illustrated in Fig. 2; and Fig. 5, a broken plan section taken as indicated at line 5 of Fig. 4.

The sprung structure comprises a plurality of parallel, cell-inclosed spring-rows A, A; and, at right angles thereto, a plurality of parallel, cell-inclosed spring-rows B, B, which are interlockingly engaged with the rows A, A by being threaded through vertical slits with which the flexible envelops of the rows A, A are provided.

Each spring-row A comprises an elongated casing 1, which may be of muslin or other flexible material, said envelop being divided into vertical cells 1^a, between which are vertical slits or openings 1^b. The en-

velop may be formed by folding a strip of cloth along its longitudinal median line and providing vertical rows of stitches 2, which divides the casing into cells. Preferably two rows of stitches are provided between adjacent cells, and the slit 1^b is formed between the two rows of stitches.

Coil springs 3 are inserted in the cells, and the cells are closed by a row of stitches 4, the upper walls of the cells being formed by the loop or fold of the material.

Each spring-row B comprises an elongated envelop or flexible casing 5, which is divided into vertical cells 5^a, by means of single vertical rows of stitches 6. Springs 7, similar to the springs 3, are inserted in the cells 5^a, and the lower ends of the cells are closed by a row of stitches 8.

The units or spring-rows are preferably completed in the manner described, and the units B are then threaded through the slits of the units A, thus causing the units to be interlocked at their points of intersection in the manner illustrated in Figs. 1 and 3, it being noted that the expanded cells of one row are engaged by the expanded cells of the intersecting row, so that the cells are nested and the springs mutually brace each other, the units being securely interlocked.

The spring structure described is preferably inclosed in a flexible casing, or cover 9, and it is noteworthy that the units may be compacted together as much as desired when inserted in the cushion casing 9.

The units can be simply and cheaply constructed, and the assembling can be easily and cheaply effected. While the cells and their inclosed springs are thus securely anchored together, and the upright position of the isolated springs is insured, the resilience of the cushion or mattress is not interfered with. The structure is cheap and durable and affords an exceedingly comfortable spring-bottom.

The foregoing detailed description has been given for clearness of understanding only, and no unnecessary limitation should be understood therefrom, but the appended claims should be construed as broadly as permissible in view of the prior art.

What I regard as new and desire to secure by Letters Patent is:

1. In a spring structure of the character set forth, the combination of a plurality

of elongated flexible envelops, each containing a plurality of springs, and a plurality of flexible envelops extending through slits in said first named envelops and each containing a plurality of springs.

5. 2. In a spring structure of the character set forth, the combination of a plurality of flexible envelops, each comprising a series of isolated cells, a plurality of flexible envelops extending through slits in said first named envelops between the cells thereof, each of said second-named envelops comprising a series of isolated cells, and coil springs confined in said cells.

10. 3. In a spring structure of the character set forth, the combination of a plurality of flexible envelops divided into cells by double rows of stitches and having slits between the rows of stitches, springs confined in said cells, a plurality of flexible envelops extending through said slits, and springs confined in said second-named envelops and disposed in spaces between said first-named envelops.

15. 4. In a spring structure of the character set forth, the combination of a plurality of flexible envelops divided into cells by double rows of stitches and having slits between

the rows of stitches, springs confined in said cells, a plurality of flexible envelops extending through said slits and each divided into a plurality of cells by stitches, and springs confined in said last named cells.

20. 5. In a spring structure of the character set forth, the combination of a plurality of parallel spring units, each comprising a flexible envelop divided into cells, and springs confined in said cells, and a plurality of spring units extending at right angles thereto and interlockingly connected therewith, each of said last-named units comprising a flexible envelop divided into cells, and springs confined in said last named cells.

25. 6. In a spring structure, an elongated flexible envelop divided into cells and provided with slits between the cells adapted to permit a similar envelop to extend therethrough, and springs confined in said cells.

ISAAC KARPEN.
